(57) **CLAIM**

The ornamental design for a pocket knife, as shown.

DESCRIPTION

FIG. 1 is an isometric view showing a pocket knife embodying the novel design;

FIG. 2 is an isometric view similar to FIG. 1 but showing the knife as it appears when an attachment ring assembly is disconnected from the knife handle;

FIG. 3 is an isometric view similar to FIGS. 1 and 2 but showing the knife as it appears when the knife blade is folded into the knife handle;

FIG. 4 is an end elevational view of the knife;

FIG. 5 is a plan view of the knife as it appears when the knife is configured as it is configured in FIG. 1;

FIG. 6 is a side elevational view of the knife showing the knife as it appears when configured as it is configured in FIG. 5;

FIG. 7 is an opposite plan view of the knife as it appears when configured as shown in FIG. 5;

FIG. 8 is an end view of the knife showing the end opposite to that end shown in FIG. 4; and,

FIG. 9 is a side elevational view showing the side opposite to that shown in FIG. 6.
